UNITED STATES PATENT OFFICE.

WILLIAM H. CLARK, OF SPENCER, NEBRASKA.

FOLDABLE EGG-TRAY STAND FOR INCUBATORS.

1,179,503.

Specification of Letters Patent. Patented Apr. 18, 1916.

Application filed June 14, 1915. Serial No. 34,007.

To all whom it may concern:

Be it known that I, WILLIAM H. CLARK, a citizen of the United States, residing at Spencer in the county of Boyd and State of Nebraska, have invented certain new and useful Improvements in Foldable Egg-Tray Stands for Incubators; and I do declare the following to be a full, clear, and exact description of the invention, such as will enable others skilled in the art to which it appertains to make and use the same.

My invention relates to improvements in devices for facilitating the turning of the eggs in incubators, and more particularly to a particular type of foldable stand pivoted to the incubator and adapted to be swung outwardly to a horizontal position in advance of the door thereof, whereby the tray of eggs may be placed upon said stand previous to and immediately after turning.

The object of the invention is to provide a device of the class described which, although being very simple and inexpensive, will be efficient in operation and will possess a number of advantageous features.

With this general object in view, the invention resides in certain novel features of construction and the unique combinations of parts to be hereinafter claimed and fully described by reference to the accompanying drawings wherein:

Figure 1 is a front elevation of an incubator equipped with a stand constructed in accordance with the invention, the stand being shown in folded position; Fig. 2 is a similar view with the stand extended; Fig. 3 is a side elevation of the front end portion of the incubator showing the stand folded; Fig. 4 is a similar view with the stand extended; Fig. 5 is a top plan view of part of the incubator and the stand in the position disclosed in Fig. 3; and Fig. 6 is a similar view showing the parts positioned as disclosed in Fig. 4.

In these drawings, which constitute a part of the application and in which like reference characters designate corresponding parts throughout the several views, the numeral 1 designates a common type of incubator having a forwardly and downwardly swinging door 2 through which the egg tray 3 may be removed for the purpose of turning the eggs.

Pivoted at 3' to the incubator at points directly below the door 2 and serving as supports for said door when swung to hori-

zontal positions, is a pair of arms 4 to which the fixed section 5 of the foldable table member 6 is secured, said member also including a movable section 7 which is hinged at 8 to the section 5, both sections being preferably constructed of crossed longitudinal and transverse bars.

When the arms 4 are swung to horizontal positions, the entire table member 6 is positioned horizontally in advance of the open door 2, said member being retained in this position by the legs 9 which are connected by a transverse bar 10, the upper ends of said legs being hinged to the section 5 of the table member 6 and being braced in respect thereto by the toggle links 11. With the parts in this position, the tray 3 may be shifted out of the incubator upon the stand, whereupon an additional tray may be placed thereover, the two trays being then inverted, whereupon the eggs are deposited from one into the other and thus turned completely over. The tray of eggs is now again inserted into the incubator, the door is closed, the section 7 is folded rearwardly upon the section 5, the toggle link braces 11 are released to allow the legs 9 to fold rearwardly, and the entire device is then swung downwardly to the position disclosed in Figs. 1, 3 and 5, the movable section 7 being now held against movement in respect to the section 5 by a hook or the like 12 shown most clearly in Fig. 5.

From the foregoing description, taken in connection with the accompanying drawings, it will be evident that although very simple and inexpensive construction has been provided for carrying out the object of the invention, the device will be efficient in operation and will greatly facilitate turning of the eggs.

In the drawings, certain specific details of construction have been shown for accomplishing probably the best results, and in the preceding such details have been described but it will be evident that I need not be restricted thereto, otherwise than to the extent that the appended claims limit me.

I claim:

1. The combination with an incubator having a forwardly and downwardly swinging door, an arm pivoted to said incubator below the door and movable to a horizontal position to receive the door thereon when the latter is opened, and a table member carried by said arm and disposed to a hori-

zontal position in advance of the door, when said arm is so disposed.

2. The combination with an incubator having a forwardly and downwardly swinging door, of a pair of arms pivoted to said incubator below the door and movable to horizontal positions to receive the door thereon when the latter is opened, a foldable table member carried by said arms and disposed to a horizontal position in advance of the door when said arms are so disposed, and foldable supporting legs for said table member.

3. An egg tray stand comprising a table member to be disposed horizontally in advance of the downwardly swinging door of an incubator, supporting legs for said table member, and attaching arms projecting rearwardly from said table member and of a length greater than the height of the incubator door, whereby to form a support for said door when swung downwardly, said arms being adapted for attachment to the incubator below the door.

4. An egg tray stand comprising a table member adapted for horizontal disposition in advance of the downwardly swinging door of an incubator, foldable supporting legs for said table member, attaching arms projecting rearwardly from the table member and of a length greater than the height of the incubator door, and hinge means on the rear ends of said arms for attachment to the incubator immediately below the door, whereby said arms may serve as supports for the door when the latter is opened.

5. An egg tray stand comprising a table member adapted to be positioned horizontally in advance of the downwardly swinging door of an incubator, said member being formed of a relatively fixed section and a

movable section hinged thereto to be swung into parallelism therewith, hook means for retaining the two sections in parallel relation, supporting legs hinged to the relatively fixed section, foldable braces for said legs, a pair of attaching arms secured to the fixed section and extending rearwardly therefrom a distance greater than the height of the door, and hinge members on the rear ends of said arms for attachment to the incubator immediately below the door, whereby said arms may serve as supports for the door when the latter is opened.

6. An egg tray stand comprising a table member for horizontal disposition in advance of the downwardly swinging door of an incubator, said member including a fixed section and a movable section hinged thereto to be folded toward the same, both sections being composed of crossed longitudinal and transverse bars, hook means for retaining the movable section folded upon the fixed section, supporting legs hinged to the fixed section, foldable braces for said legs, a pair of substantially horizontal attaching arms secured to the fixed section and extending rearwardly therefrom a distance greater than the height of the incubator door, and hinge members on the rear ends of said arms for attachment to the incubator immediately below the door, whereby said arms may serve as supports for the door when the latter is opened.

In testimony whereof I have hereunto set my hand in presence of two subscribing witnesses:

WILLIAM H. CLARK.
